US0D1101141S

(12) **United States Design Patent** (10) Patent No.: **US D1,101,141 S**
(45) Date of Patent: ** Nov. 4, 2025

(54) **CATHETER**(71) Applicant: **C. R. Bard, Inc.**, Franklin Lakes, NJ (US)(72) Inventors: **Jason R. Stats**, Layton, UT (US); **Daniel B. Blanchard**, Bountiful, UT (US)(73) Assignee: **C. R. Bard, Inc.**, Franklin Lakes, NJ (US)(**) Term: **15 Years**(21) Appl. No.: **29/757,781**(22) Filed: **Nov. 9, 2020****Related U.S. Application Data**

(60) Division of application No. 29/654,527, filed on Jun. 25, 2018, now Pat. No. Des. 903,101, which is a continuation of application No. 29/545,436, filed on Nov. 12, 2015, now abandoned, which is a continuation of application No. 14/702,580, filed on May 1, 2015, now Pat. No. 9,950,139, which is a continuation-in-part of application No. 14/099,050, filed on Dec. 6, 2013, now Pat. No. 9,872,971, which is a continuation-in-part of application No. 13/107,781, filed on May 13, 2011, now Pat. No. 8,932,258.

(51) LOC (15) Cl. **24-02**

CLAIM

The ornamental design for a catheter, as shown and described.

DESCRIPTION

The application file contains at least one drawing executed in color. Copies of this patent application publication with color drawings will be provided by the Office upon request and payment of the necessary fee.

FIG. 1 is a top perspective view of a first embodiment of a catheter with a purple colored hub and a pink colored strain relief portion;

FIG. 2 is a bottom perspective view of the catheter illustrated in FIG. 1 with a purple colored hub and a pink colored strain relief portion;

FIG. 3 is a first side view of the catheter illustrated in FIG. 1 with a purple colored hub and a pink colored strain relief portion;

FIG. 4 is a second side view of the catheter illustrated in FIG. 1 with a purple colored hub and a pink colored strain relief portion;

FIG. 5 is a third side view of the catheter illustrated in FIG. 1 with a purple colored hub and a pink colored strain relief portion;

FIG. 6 is a fourth side view of the catheter illustrated in FIG. 1 with a purple colored hub and a pink colored strain relief portion;

FIG. 7 is a rear view of the catheter illustrated in FIG. 1 with a purple colored hub and a pink colored strain relief portion catheter;

FIG. 8 is a front view of the catheter illustrated in FIG. 1 with a purple colored hub;

FIG. 9 is a top perspective view of a second embodiment of a catheter with a pink colored hub and a purple colored strain relief portion;

FIG. 10 is a bottom perspective view of the catheter illustrated in FIG. 9 with a pink colored hub and a purple colored strain relief portion;

FIG. 11 is a first side view of the catheter illustrated in FIG. 9 with a pink colored hub and a purple colored strain relief portion;

FIG. 12 is a second side view of the catheter illustrated in FIG. 9 with a pink colored hub and a purple colored strain relief portion;

FIG. 13 is a third side view of the catheter illustrated in FIG. 9 with a pink colored hub and a purple colored strain relief portion;

FIG. 14 is a fourth side view of the catheter illustrated in FIG. 9 with a pink colored hub and a purple colored strain relief portion;

FIG. 15 is a rear view of the catheter illustrated in FIG. 9 with a pink colored hub and a purple colored strain relief portion;

FIG. 16 is a front view of the catheter illustrated in FIG. 9 with a pink colored hub;

FIG. 17 is a top perspective view of a third embodiment of a catheter with a purple colored hub and a green colored strain relief portion;

FIG. 18 is a bottom perspective view of the catheter illustrated in FIG. 17 with a purple colored hub and a green colored strain relief portion;

FIG. 19 is a first side view of the catheter illustrated in FIG. 17 with a purple colored hub and a green colored strain relief portion;

FIG. 20 is a second side view of the catheter illustrated in FIG. 17 with a purple colored hub and a green colored strain relief portion;

FIG. 21 is a third side view of the catheter illustrated in FIG. 17 with a purple colored hub and a green colored strain relief portion;

FIG. 22 is a fourth side view of the catheter illustrated in FIG. 17 with a purple colored hub and a green colored strain relief portion;

FIG. 23 is a rear view of the catheter illustrated in FIG. 17 with a purple colored hub and a green colored strain relief portion;

FIG. 24 is a front view of the catheter illustrated in FIG. 17 with a purple colored hub;

FIG. 25 is a top perspective view of a fourth embodiment of a catheter with a purple colored hub and a blue colored strain relief portion;

FIG. 26 is a bottom perspective view of the catheter illustrated in FIG. 25 with a purple colored hub and a blue colored strain relief portion;

FIG. 27 is a first side view of the catheter illustrated in FIG. 25 with a purple colored hub and a blue colored strain relief portion;

FIG. 28 is a second side view of the catheter illustrated in FIG. 25 with a purple colored hub and a blue colored strain relief portion;

FIG. 29 is a third side view of the catheter illustrated in FIG. 25 with a purple colored hub and a blue colored strain relief portion;

FIG. 30 is a fourth side view of the catheter illustrated in FIG. 25 with a purple colored hub and a blue colored strain relief portion;

FIG. 31 is a rear view of the catheter illustrated in FIG. 25 with a purple colored hub and a blue colored strain relief portion;

FIG. 32 is a front view of the catheter illustrated in FIG. 25 with a purple colored hub;
FIG. 33 is a top perspective view of a fifth embodiment of a catheter;
FIG. 34 is a bottom perspective view of the catheter illustrated in FIG. 33;
FIG. 35 is a first side view of the catheter illustrated in FIG. 33;
FIG. 36 is a second side view of the catheter illustrated in FIG. 33;
FIG. 37 is a third side view of the catheter illustrated in FIG. 33;
FIG. 38 is a fourth side view of the catheter illustrated in FIG. 33;
FIG. 39 is a rear view of the catheter illustrated in FIG. 33; and,
FIG. 40 is a front view of the catheter illustrated in FIG. 33. The broken lines immediately adjacent the shaded areas represent the bounds of the claimed design while all other broken lines are directed to environment; the broken lines form no part of the claimed design.
